US00D814714S

(12) **United States Design Patent** (10) Patent No.: **US D814,714 S**
(45) Date of Patent: ** Apr. 3, 2018

(54) **FOOD DISPENSER**

(71) Applicant: **Doskocil Manufacturing Company**,
Arlington, TX (US)

(72) Inventors: **David Simon**, Lakeland, FL (US);
David Veness, Fort Worth, TX (US);
Nicholas Baker, Fort Worth, TX (US)

(73) Assignee: **DOSKOCIL MANUFACTURING COMPANY, INC.**, Arlington, TX (US)

(**) Term: **15 Years**

(21) Appl. No.: **29/582,259**

(22) Filed: **Oct. 26, 2016**

(51) LOC (11) Cl. **30-07**

(52) U.S. Cl. USPC **D30/122**

(57) **CLAIM**

The ornamental design for a food dispenser, as shown and described.

DESCRIPTION

FIG. 1 is a front perspective view of a food dispenser in accordance with our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The underside area depicted in broken lines in FIG. 7 represents an unclaimed portion of the food dispenser and is shown merely for purposes of illustration.

1 Claim, 7 Drawing Sheets
